United States Patent Office

Des. 186,270
Patented Oct. 6, 1959

186,270

CHAIR

Trace Christenson and Wayne W. Good, Sturgis, Mich.,
assignors to Harter Corporation, Sturgis, Mich.

Application January 16, 1959, Serial No. 54,199

Term of patent 14 years

(Cl. D15—1)

Fig. 1 is a front perspective view of a chair embodying our invention.

Fig. 2 is a side elevational view, and

Fig. 3 is a rear view.

Fig. 4 is a cross-sectional view taken on line 4—4 of Fig. 1.

The side not shown is a duplicate of the side shown in Fig. 2.

We claim:

The ornamental design for a chair, as shown and described.
